UNITED STATES PATENT OFFICE.

MIKE LUTENBERGER, OF BLOCTON, ALABAMA.

ROCKING-CHAIR.

1,006,963.

Specification of Letters Patent.

Patented Oct. 24, 1911.

Application filed April 21, 1911. Serial No. 622,513.

To all whom it may concern:

Be it known that I, MIKE LUTENBERGER, a subject of the King of Hungary, residing at Blocton, in the county of Bibb and State of Alabama, have invented certain new and useful Improvements in Rocking-Chairs, of which the following is a specification, reference being had therein to the accompanying drawing.

10 This invention relates to rocking chairs, and the primary object of my invention is to furnish a rocking chair with positive and reliable means, in a manner as will be hereinafter set forth, for maintaining a circulation of air in the vicinity of the chair, whereby the chair can be comfortably used in the summer time.

Another object of the invention is to provide a chair with a cooling chamber in which 20 can be stored fruit, bottles of liquid and other matter for the convenient use of the occupant of the chair.

With the above and other objects in view, the invention resides in the novel construction, combination and arrangement of parts 25 to be hereinafter specifically described and then claimed.

Reference will now be had to the drawings, wherein like numerals of reference designate corresponding parts throughout the 30 several views, in which:—

Figure 1 is a front elevation of the chair with the seat cover thereof raised, Fig. 2 is a vertical sectional view of the chair, Fig. 35 3 is a horizontal sectional view of the same, and Fig. 4 is an enlarged rear elevation of an electric fan and motor adapted to form 40 part of the chair.

A rocking chair in accordance with this 45 invention comprises rockers 1 having vertical arm posts 2 and back posts 3. The arm posts 2 are connected by transverse rounds 4 and the back posts 3 by transverse rounds 5 and 6. The arm posts 2 are connected to the 50 back posts 3 by longitudinal rounds 7 and the upper ends of the arm posts 2 support the forward ends of arms 8 and 9 having the rear ends thereof suitably connected to the posts 3. The uppermost rounds 4 and 5 support a perforated seat 10 and this seat is provided with a cover 11 having a depending front piece 12 and a back piece 13, said pieces being suitably connected to the chair. The arms 8 and 9 have vertical covers 14 and 55 the back posts 3 are connected upon the rear sides by a cover 15.

Arranged upon the lowermost rounds 4 and 5 is a platform 16 and mounted upon said platform is a rectangular structure having longitudinal walls 17, a front wall 18, a rear wall 19 and an intermediate partition 20, the partition 20 and the walls 18 and 19 having longitudinally alining openings 21. The partition 20 forms two compartments within the structure and in the rear compartment there is located an electric fan 22 of the ordinary and well known type, the fan—*inter alia*—embodying a bladed wheel 23, a crank shaft 24 and a motor 25. In the front compartment there is placed a box 26 having a lid 27 and in the box can be placed any suitable matter.

Mounted upon the platform 16 at the sides of the structure are batteries 28 preferably of the dry cell type, these batteries being 75 retained upon the platform by straps 29 mounted over said batteries. The poles 30 of the batteries are connected by wires 31. The pole 32 of one battery is connected by a wire 33 to a conventional form of knife 80 switch 34 arranged upon the under side of the arm 9, and said knife switch is connected by another wire 35 to the binding post 36 of the motor 25. The other binding post 37 of the motor is connected by a wire 38 to the 85 pole 39 of the other battery. When the knife switch is closed, as shown in Fig. 2, a circuit is completed through the batteries 29 and the motor 25, whereby the fan will be operated to produce a suction of air through the 90 opening 21 in the rear wall 19, the air being exhausted through the opening 21 in the front wall 18 of the housing, thereby maintaining a circulation of air through the front compartment of the housing. The circulation of air beneath the seat 10 maintains the same in a cooled condition and as the air in the vicinity of the rocking chair will be agitated, the occupant of the chair can comfortably use the same in extremely warm 100 weather.

What I claim is:—

1. The combination with a rocking chair having rounds, arms, and a perforated seat, of a platform supported by some of said rounds, 105 a housing arranged upon said platform and having the front and rear walls thereof provided with openings, an electric fan located in said housing adjacent to one of said openings for forcing air through the housing and 110 operable independently of the rocking movement of the chair, batteries mounted upon

- 5 said platform at the outer sides of said housing and in circuit with said fan, and a knife switch arranged under one of said arms and adapted to control the circuit 40 through said batteries and said fan.
- 10 2. The combination with a rocking chair having rounds, a seat and arms, of a platform carried by some of said rounds, a housing arranged upon said platform and having openings formed therein, an electric 45 forcing air through the housing and operable independently of the rocking movement of the chair, batteries arranged upon said platform and in circuit with said fan, a switch carried by one of said arms and adapted to control the circuit through said fan and said batteries; and covers arranged 50 upon the seat and sides of said chair adjacent to said housing, substantially as described.
- 15 3. In combination, a rocking chair provided with a perforated seat, means to constitute a compartment arranged below the seat and having each end open, means within 55 said compartment and operable independently of the rocking movement of the chair for forcing air through said compartment, and means carried by the chair for controlling the operation of said air forcing means.
- 20 4. In combination, a rocking chair provided with a perforated seat and a compartment below said seat, said compartment having each end open, electrical means 60 mounted in said compartment for forcing air therethrough and operable independently of the rocking movement of the chair, and means carried by one of the arms of the chair for controlling the operation of 65 said electrical means.
- 25 5. In combination, a rocking chair provided with a perforated seat, a platform arranged below said seat and supported by the frame of the chair and forming a compartment, an electrically operated means mounted upon said platform and operable independent of the rocking movement of the chair for forcing air through said compartment, a source of electrical energy 50 mounted upon said platform, circuit forming wires between said means and said source, and means carried by the frame of the chair for opening and closing the circuit.
- 30 6. In combination, a rocking chair provided with a perforated seat and a pair of arms, means to constitute a compartment arranged below the seat and having each of its end walls formed with an opening, an electrical means within said compartment and operable independent of the rocking movement of the chair for forcing air through said compartment, and means carried by one of the arms of the chair for controlling operation of the said air forcing means.
- 35 7. In testimony whereof I affix my signature in the presence of two witnesses.

MIKE LUTENBERGER.
